Curt B. Muller.

UNITED STATES PATENT OFFICE.

JOSEPH SCHULTZ, OF CLEVELAND, OHIO.

INKING SURFACE CLEANSER.

Application filed August 2, 1926. Serial No. 126,491.

My invention pertains to an inking surface cleanser and more particularly to an appliance for removing ink of one color from the inking rollers of a printing press.

5 The manual removal of the ink from printing rollers is even to-day still being practiced, but is a laborious, untidy and time consuming procedure. Accordingly, the object of my invention is to provide a mechanical device 10 for cleansing the inking rolls and for accomplishing it in much less time. A further object has been the development of an adaptation both for rotary and for flat bed presses. Still another object has been the design of an 15 appliance of the character stated which would automatically convey the ink elsewhere as it is scraped from the rolls or rollers—in the exemplification shown accomplished by a suction agency. Scraping blade adjustments, 20 and in the case of use upon a flat bed press an intermittently operating shifting device constitute another feature of my invention.

It is to be realized that the scope of my invention comprehends many equivalent constructions and some changes in practicing the 25 method. The showing of the drawings and the particular description are merely a specific exemplification.

Adverting to the drawings:

30 Figure I is a broken plan view of the essential cooperating elements of a flat bed press showing my invention associated therewith.

Figure II is a side elevation viewed on line

35 II—II of Figure I.

Figure III is a cross-section on line III—III of Figure II.

Figure IV is an enlarged cross-section on line IV—IV of Figure III.

40 Figure V is a fragmentary front elevation of a portion of a rotary press showing a modified form of my scraping and suction head in operating position with respect thereto.

Figure VI is an end elevation on line

45 VI—VI of Figure V.

Figure VII is a vertical cross-section on line VII—VII of Figure V.

Figure VIII is an enlarged cross-sectional view of the scraping and suction head.

50 Figure IX is a plan section on line IX—IX of Figure VIII drawn to a reduced scale.

The figures on Sheet 1 illustrate the association of my appliance with so much of a standard flat-bed press as suffices to make

55 clear the cooperating arrangement. The press includes a frame 1, carrying near one

end a series of inking rollers 2 beneath which a carriage 3 reciprocates in a manner so well known to the art as not to require either detailed illustration or further explanation. 60

Two parallel side members 3' of the carriage 3 are fashioned, according to my invention with depressed upper track surfaces 4 merging at opposite ends with inclined track surfaces 5 and 6 respectively. Near opposite ends of the carriage 3 I provide upstanding fingers 7 and 8 for a purpose to be hereinafter explained. The carriage supports an inking plate 9 and a type bed 10 both of which when actuated will effect contact with the rollers 70 2, whereby ink of any particular color is periodically transferred thereto.

Opposite sides of the frame 1 carry opposed brackets 11, on which are mounted a pair of structures 12, of peculiar formation 75 to include vertical openings, on which are slidably mounted a pair of blocks 13 respectively adapted to be held in a raised position by pins 13^a occupying registering holes in the structures 12 and blocks 13, each carrying on 80 its lower end a roller 14 adapted to rotate in engagement with the upper surfaces of the side members of the carriage 3 and in engagement with the surfaces 4, 5 and 6 thereof, during the reciprocation of the carriage. 85 It should be understood that when either of the sloping surfaces 5 or the sloping surfaces 6 engage the rollers 14, the blocks 13 will be raised or lowered depending upon the inverse directions of movement, indicated by 90 the arrows in Figure II. Each of the blocks 13 carries a pair of divaricating arms 15 in which set screws 16 are adjustably mounted to converge in an upward direction along lines forming an angle of nearly ninety degrees. 95

Mounted in the upper portions of the blocks 13, so as to extend across the carriage 3, is a shaft 17 which is provided near each end with an extension 18 carrying a lever 19 which is re-actingly connected with a downwardly extending spring to a point 20 on the block 13 and which point is located in the vertical axial plane of the shaft 17. The function of the spring 20 is a common expedient whereby any structure carried by the shaft 17 will be pulled and yieldingly held toward one side or the other of the dead center position. The structure composing a part of my cleansing appliance is fixedly carried upon, so as to turn with, the shaft 17 and comprises, as exemplified, a frame 21 extend-

ing from side to side. The frame 21 is of hollow construction and a suction pipe 22 enters the top thereof near one end to communicate with one portion 23 of a manifold arrangement of passages. The duct 23 communicates at its lower middle point or inlet end with an enlarged hollowed portion 24 in which are arranged a row of baffles 25 properly arranged and dimensioned to equalize the suction effect lengthwise of the structure, which is to say, crosswise of the carriage 3. Scrapers 26 and 27 are secured on opposite sides of the frame 21, by means of screws 28 which will permit of effecting adjustment by reason of passing through slots in the scrapers. As is to be observed in Figures IV, the edges of the blades 26 and 27 project a short distance beyond the lower end of the frame 21 and are intended alternately to 20 scrape the inking plate 9 each during one direction of travel of the latter, as will be described. Projecting from opposite ends of the scraper carrying frame 21 are lugs 29, shown in Figures I and III, with which the 25 fingers 7 and 8 are respectively adapted periodically to engage. It is to be understood that a suitable suction agency or exhaust fan, not shown, is to be operatively connected with the pipe 22.

30 The operation is as follows:

After a printing job has been run in one color and it is desired to prepare the press for printing with a different color of ink my cleansing appliance may be put into service 35 by attaching it or by shifting a part or parts thereof from any previously chosen inutile position. When the parts of my cleanser are connected for operation with the scraping elements 26 and 27 properly adjusted and their 40 oscillating range of movement properly prescribed by the set screws 16, one or the other of the blades will scrape the inking plate or disc 9 during each direction of its reciprocal travel. In the position in which the scraping 45 appliance proper appears in full lines in Figure II the inking plate 9 will be moving in the direction indicated by that one of the two arrows illustrated in Figure II which is to the right, whereas, during the time that the 50 inking plate is traveling in the opposite direction or to the left and being scraped the blade 26 will be functioning while its supporting frame 21 occupies the position shown in dotted lines in Figure II. It is, of course, 55 essential that the scraping blades do not come into contact with the type form 10 and it is for the purpose of avoiding such contact that the blocks 13 are vertically slideable and the inclined or sloping surfaces 6 provided to 60 raise the blocks 13 and hence the frame 21 with its blades when the carriage 3 is moving to the left and the rollers 14 ride up the surfaces 6. It is also necessary to elevate the blocks 13 and raise the blades (preparatory to 65 turning the shaft 17 and therefore swinging

the frame 21) when the carriage 3 reaches the limit of its movement toward the right, as viewed in Figure III, and it is for accomplishing this that the inclined surfaces 5 are provided. The periodical swinging shift in 70 position of the frame 21 is automatically effected at each limit of movement of the carriage 3 in either direction and after the rollers 14 have ridden over either the surfaces 5 or the surfaces 6. Just prior to reaching the 75 limit of movement to the right, the fingers 7 will impinge against the lugs 29 and throw the frame 21, first against the action of the springs 20 and then past the dead center position and from its full line position in Figure II to the position in which it is shown in dotted lines. In so doing the blade 26 will have been brought to a position in which it can scrape the plate 9 after the rollers 14 have descended the inclines 5 during the return 80 movement to the left at the end of which direction of movement the fingers 8 will in turn engage the lugs 29 and again swing the frame 21 to the position in which it is shown in full lines in Figure II preparatory to having the 85 blade 27 functionate to scrape the plate 9 after the rollers 14 have descended the inclines 6. In the meantime, the suction effect will have continually removed ink while being scraped from the plate 9 through the 90 hollowed portions 24, thence through the duct 23 and through the pipe 22 to a suitable catch basin. The adjustment permitted of the blades 26 and 27 is, of course, in order to compensate for wear to the operating extremities 95 thereof.

The modification illustrated on Sheet 2, Figures V to IX inclusive refers to a somewhat simplified adaptation to presses with rotating inking rollers. A frame 30 is illustrated fragmentarily as carrying, in appropriate bearings 31, one inking roller 32 of a series, the remainder of which need not be shown, though it should be understood as in frictional contact therewith. Adjacent each 100 end of the roller 32 the frame 30 is formed with a downwardly sloping support 33 to which is detachably secured a bracket 34 through the agency of bolts 35. The brackets 105 each include an upward extension 36 in which studs 37 are latch mounted for turning movement. The two studs 37 are part of a manifold-hollowed frame 38. Adjusting levers 39 are pivoted to ears 40 on the brackets 34 and each is provided with a handle 41. Links 42 connect the free ends of the levers 39 with the outer end of the frame 38 at 43 whereby, as will be readily perceived, a swinging movement imparted to the handles 41 will swing the inner end of the frame 38 or that edge of it which is nearest the roller 32 toward or away from the latter and hence toward and away from the functioning position of a single scraping blade carried by the frame 38 and to be now described.

The frame 38 is fashioned with a duct 44 with one end of which a suction pipe 45 is connected. The opposite end of the duct 44 communicates with a manifold passage 46 formed by the interpositioning of a portion 47 and the ends of the passage 46 communicates with inlets 48 provided between minor portions or baffles 49. A scraper 50 is adjustably mounted, by means of screws 51 passing through elongated slots in the blade, to the lower side of the frame 38 and so that one extremity 52 of the blade projects beyond the inner end of the frame. When a printing job is being run on the press the levers 41 will be depressed to disengage the blade 50 from the roller 32 and after completion of the job, when it may be desired to remove the ink, the levers 41 are simply to be raised to enable the scraper 50 progressively to scrape and remove the ink.

I claim:—

1. The combination with a flat-bed printing press having a reciprocating inking plate, of a scraping appliance swingably mounted over and adapted to scrape said plate, springs for resisting the initiation of a shift in position of said appliance, means for creating a suction effect at the point of scraping application, the arrangement being such that said plate during its travel alternately shifts the position of said appliance.

2. The method of cleansing an ink carrying surface of a printing press which consists in alternately scraping said surface by presentation thereagainst of a blade at a predetermined angle thereto and again by presentation of another blade at a substantially similar angle while said surface reciprocates, while continuously applying a suction effect to the portion of said surface being scraped.

3. The method of cleansing a flat reciprocating ink carrying surface of a printing press which consists in scraping said surface by presentation thereagainst of one of two blades from above during one direction of movement, separating said blade and surface by simultaneously raising said blades near one limit of travel of the surface and then bringing the other blade into functioning position during movement in the opposite direction.

4. In an appliance of the character described, the combination of an ink-carrying member, a device adapted to scrape said member, means for actuating one of said parts relative to the other for performing the scraping operation, means for effecting a separating movement between said member and device and a suction nozzle carried by said device and having an opening adapted to assume a position of proximity to the portion of said member being scraped.

5. In an appliance of the character described, the combination of a frame, an ink-carrying member movably mounted thereon,

a device movably carried by said frame and adapted to scrape said member, means responsive to the movement of said member for actuating said device in one direction, automatically operating means for periodically effecting a separating movement of said device and suction means operatively associated with said device.

6. In an appliance of the character described, the combination of an ink-carrying member, a double blade scraper, means for reciprocating said member, means for reciprocating said blades transversely to the movement of said member and automatically operating means for periodically effecting a swinging movement of said blades to permit them alternately to contact said member during its movements in reverse directions.

7. The combination with a movable carriage of a printing press, of a cleaning appliance, said appliance being adapted and arranged to be first raised and then swung through an arc by said carriage devices on said carriage and appliance respectively adapted periodically to raise said appliance and different devices on said carriage and appliance respectively adapted periodically to coact to swing said appliance.

8. The combination of a frame, a structure including an ink-carrying element and movably mounted on said frame, an appliance for scraping ink from said element and adapted to be periodically shifted in two distinct ways with respect thereto at predetermined stages of travel of said element, and mechanisms for successively actuating said appliance first in one way and then in another.

9. The combination with a flat-bed printing press having a reciprocating inking plate, of a scraping appliance movably mounted over and adapted to scrape said plate, means for creating a suction effect at the point of scraping application, and means including cooperating devices on said plate and appliance respectively adapted during the travel of the former automatically to shift the position of said appliance.

10. The combination with a flat-bed printing press having a reciprocating inking carriage fashioned with track surfaces of different elevation, a roller structure adapted to contact one of said track surfaces and to rise or fall according to the elevation of the track surface moving in engagement with it, a scraping appliance swingably mounted on said roller structure and adapted to be turned through a predetermined arc when said structure is in a raised position and distinct automatically operating means for swinging said appliance at prescribed operating intervals.

11. The combination with a flat-bed printing press having a reciprocating inking carriage symmetrically fashioned on opposite sides with track surfaces of different elevation, fixed brackets, roller structures mounted

for movement on said brackets and adapted to contact said track surfaces and also adapted to rise or fall according to the elevation of the track surface moving in engagement with it, a shaft mounted in said roller structures, a scraping appliance mounted on said shaft and adapted to be turned through a predetermined arc when said shaft is in a raised position and distinct automatically operating means including periodically engageable parts on said carriage and appliance for swinging the latter near each limit of movement of said carriage.

12. In a device of the character described, the combination of a printing carriage, a structure disposed crosswise of said carriage and movable relatively thereto, said structure including a pair of spaced stops, a scraping appliance pivotally mounted on said structure for swinging movement between said stops and including a scraping element and projecting members carried by said carriage and appliance respectively adapted periodically to engage to effect a swinging shift in position of said appliance from one stop to the other.

13. In an appliance of the character described, the combination of a frame, a carriage reciprocably mounted thereon, blocks reciprocably mounted at opposite sides of said frame for movement toward and away from said carriage, spaced stops on said blocks, a scraping appliance including a shaft mounted to turn on said blocks and between said stops, a lever on said shaft, a spring connecting the free end of said lever with said frame and automatically operating means for periodically swinging said appliance from one stop to the other.

14. In an appliance of the character de-

scribed, the combination of a frame, a carriage reciprocably mounted thereon, blocks reciprocably mounted at opposite sides of said frame for up and down movement relative to said carriage, spaced stops adjustably mounted on said blocks, a scraping appliance including a shaft mounted to turn on said blocks and between said stops, automatically operating means for periodically swinging said appliance from one stop to the other and automatically operating means for periodically raising and lowering said blocks in timed relation to the swinging movement of said appliance.

15. In a printing press the combination of a movable ink-carrying element, a movable support, a scraping appliance movably mounted on said support adjacent to said element and adapted to scrape the latter, automatically operating means for moving said support and means including cooperating devices on said element and appliance respectively adapted during travel of the former automatically to shift the position of said appliance relative to said support.

16. In a device of the character described, the combination of a pair of structures disposed crosswise of each other and movable in relatively transverse directions, a scraping element pivotally mounted on one of said structures and adapted to be swung through a predetermined arc about its pivotal axis and a tension spring arranged alternately to swing to and beyond a dead center position in response to the swing of said scraping element and thereby to urge or resist the movement of said scraping element about its pivotal axis.

Signed by me, this 27th day of July, 1926.
JOSEPH SCHULTZ.
